[57] CLAIM

The ornamental design for a pivotable display holder and dispenser for sheet material, as shown and described.

DESCRIPTION

FIG. 1 is a perspective view of a pivotable display holder and dispenser for sheet material showing my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left side elevational view thereof; and

FIG. 7 is a right side elevational view thereof.

The broken lines shown throughout FIGS. 1-6 indicate environmental structure and form no part of the claimed design.
